DESIGN FOR A VANITY CASE OR LIKE ARTICLE

Alfred F. Reilly, North Attleboro, Mass., assignor to Evans Case Company, a corporation of Massachusetts

Application October 17, 1935, Serial No. 59,099

Term of patent 3½ years

To all whom it may concern:

Be it known that I, Alfred F. Reilly, a citizen of the United States, residing at North Attleboro, in the State of Massachusetts, have invented a new, original, and ornamental Design for a Vanity Case or Like Article, of which the following is a specification, reference being had to the accompanying drawing, forming a part hereof.

In the accompanying drawing Figure 1 is a front elevational view of a vanity case or like article embodying my new design and

Fig. 2 is a side elevational view thereof.

I claim:

The ornamental design for a vanity case or like article substantially as shown.

ALFRED F. REILLY.
